INTERCOMMUNICATIONS SET

Louis Lucien Lepoix, Baden-Baden, Germany, assignor to
La Telephonie Industrielle et Commerciale "Telic"

Filed Apr. 5, 1971, Ser. No. 131,146

Term of patent 14 years

Int. Cl. D14—03

U.S. Cl. D26—14

FIG. 1

FIG. 2

FIG. 3

FIG. 1 is a perspective view of an intercommunications set showing my new design;

FIG. 2 is a perspective view as seen from the opposite side of FIG. 1; and

FIG. 3 is a rear perspective view thereof.

I claim:

The ornamental design for an intercommunications set, as shown and described.
